CLAIM

The ornamental design for an oral care implement, as shown and described.

DESCRIPTION

FIG. 1 is a right, front perspective view of an oral care implement showing our new design;

FIG. 2 is a left, front perspective view thereof;

FIG. 3 is a right, rear perspective view thereof;

FIG. 4 is a left, rear perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The broken lines showing the brush head and the remainder of the handle illustrate portions of the oral care implement that form no part of the claimed design.

1 Claim, 5 Drawing Sheets---
